TAPE PLAYER FOR VEHICLES

Nozomu Matsumoto, Tokyo, Japan, assignor to Pioneer
Kabushiki Kaisha (also trading as Pioneer Electronic
Corporation), Tokyo, Japan

Filed Apr. 20, 1970, Ser. No. 22,507

Claims priority, application Japan Oct. 21, 1969

Term of patent 14 years

Int. Cl. D14—01

U.S. Cl. D26—14

FIG. 1

FIG. 2

FIG. 3

FIG. 4

FIG. 5

FIG. 6

FIG. 7

FIG. 1 is a front elevational view of the tape player for vehicles, showing my new design.

FIG. 2 is a rear elevational view thereof,

FIG. 3 is a top plan view thereof,

FIG. 4 is a bottom plan view thereof,

FIG. 5 is a right side elevational view thereof,

FIG. 6 is a front perspective view of a tape player for vehicles showing another embodiment of my new design,

FIG. 7 is a front elevational view of a tape player for vehicles showing still another embodiment of my new design.

I claim:

The ornamental design for a tape player for vehicles, as shown and described.
